W. H. Reid.

UNITED STATES PATENT OFFICE.

LUELLA CORNELL, OF BROOKLYN, NEW YORK.

CAR-UNCOUPLER.

1,367,020.

Specification of Letters Patent.

Patented Feb. 1, 1921.

Application filed June 30, 1920. Serial No. 392,970.

To all whom it may concern:

Be it known that I, LUELLA CORNELL, a citizen of the United States, and a resident of Brooklyn, county of Kings, and State of New York, have invented certain new and useful Improvements in Car-Uncouplers; and I do hereby declare the following to be a full, clear, and exact description of one form of my invention, reference being had 5 to the accompanying drawing, forming a part of this specification.

This invention has reference to mechanism for operating the coupling means at the ends of railway cars, at one or more 15 places remote from the coupler; whereby the train men are not required to actuate the coupler itself.

The object of the invention is to provide an improved and efficient uncoupling device, 20 which may be readily applied and operated in connection with the various forms of standard car couplers, in general use by railroads; and which further will comply with the requirements, and the preferred construction made standard by the Master Car 25 Builders Association.

In the accompanying drawing illustrating a modification of my invention, Figure 1 shows the end portion of a conventional 30 form of railway car generally known as a box car.

Fig. 2 is a plan view of the uncoupling members.

Fig. 3 shows the uncoupling lever that 35 operates from the side of the car.

Fig. 4 shows enlarged the hook on the end of the uncoupling rod.

Fig. 5 shows the same operating means as applied to a freight car of the gondola type, 40 with the end of the car in lowered position, and the uncoupling device disconnected.

As shown in Figs. 1-4, the box car is set forth as having an end member 2, and a sill 3. The usual form of coupler 4, of the 45 Janney, or Gould type, is shown, provided with a pin 5 having an opening or eye 6 at the top; which member is usually known as a lock link of the coupler. This form of coupler is uncoupled by the operation of 50 raising this pin or link, and the purpose of the present invention is to provide a device for raising this link, to be operated by a person on the top 7 of the car, and also from one side of the car, so that such person does 55 not have to go between the cars, if on the

ground, nor does such person have to come down if on top of the box car.

For this purpose I provide an operating angular rod 8 extending from the sill 3 up to the top of the car, and guided for movement upwardly by suitable means, such as an eye bolt 9', the rod having a handle 10 at the top to be readily grasped by the operator. The lower end of this operating rod is provided with means for detachably 60 connecting it with the pin eye 6 and by a direct connection having no intermediate links or rings, to comply with the requirements of the M. C. B.

In the form shown the rod 8 has its lower 70 end portion 9 extending laterally from the car end 2, and is bent to form a hook 12 at this end, that can be passed through the eye 6 of the coupler pin, as clearly shown in Fig. 2. This hook is preferably pro- 75 vided with a keeper shown in the form of a spring tongue 13, that will bend to admit the link but prevent the loosening of the hook from the pin, until the tongue is manipulated. Yet the hook can be readily 80 disconnected by the trainman when desired.

This tongue is preferably secured by integral means, such as bending over the edges 14, 14 of a recess in the hook that can be done by a quick heat process, that will per- 85 mit the sides of this recess to bend over the spring tongue, without drawing the temper of the spring. The plan view of Fig. 2 shows the pin or the lock link in its normal position with the eye opening at the sides, 90

and the hook 12 is normally in a horizontal plane as shown in this view. Since the operating rod 8 is attached to the car end only by the guiding eye bolt at 9', it can be readily operated by the trainman to be 95 unhooked, and again hooked in the eye of the coupler pin or link. It will be readily understood that when the hook is engaged in the pin eye, the trainman on top of the car has merely to grasp the handle 10 and 100 pull upward on the operating rod, that will withdraw the pin and uncouple the car.

I further provide means for operating the coupler pin from the side of the car, that is detachably connected with the described 105 operating means. In Fig. 3 I show a simple lever 15 that has an opening 16 at its intermediate part, through which passes a bolt 17 to pivot this lever on the sill 3. The lever will have its outer end 18 adjacent the 110

end of the sill, which is one side of the car, while the other end of the lever 15 is provided with an angular loop 19 as shown. This loop will serve to receive and inclose 5 the lateral extension 9 of the operating rod 8, as shown in Figs. 1 and 2. By merely pressing downward on the outer end 18 of the lever 15, this lever will press upward on the rod portion 9, and therefore will raise 10 the pin 5 in the coupler, effecting the uncoupling operation. It will be understood that this uncoupling lever has a direct connection with the operating rod 9, and no loose links are employed, that is considered 15 objectionable in this mechanism.

The special advantage of such a construction appears when it is applied to a car whose end member is hinged to swing inwardly and downwardly to lie on the 20 bottom of the car. In Fig. 5 I show a car of this type, in which the body 20 has its end member 21 hinged at its lower edge 22 to swing down on the car bottom. The same form of uncoupling mechanism that 25 I have described, is applied to this latter, but the operating rod 8 is simply made shorter, to reach only to the top of the end member 21. Otherwise the construction is identical, and also the operation. When a 30 mechanism of this character, on this form of car is in operative position with the end member vertical, and it is desired to swing the end member down to the horizontal position, it is only necessary to disconnect the 35 snap hook 12 from the eye of the pin 5, and then move the lateral portion 9 of the operating rod to one side, bringing it out of the link 19 of the lever 15. This will obviously leave the operating member 8, and its lateral 40 portion 9, entirely free, both of the coupler pin and of the lever 15. The end member 21 can now be swung down on the car bottom, as indicated in Fig. 5, it being connected with the car only by the eye bolt 9'. Obviously 45 the lateral portion 9 of the rod can swing down to a horizontal position, as shown.

It will be readily understood that a mechanism of this construction is very simple

and cheap to construct, comprising merely 50 the operating rod with its hook and the side lever, with the two fastening means for such members. These parts connect direct with the usual form of coupler pin.

It is to be understood that various changes 55 can be made by those skilled in this art, within the purview of the claims, without departing from the spirit and scope of my invention.

The present invention is an improvement 60 on the uncoupling device set forth in U. S. Letters Patent No. 1,298,669 granted to me April 1, 1919.

What I claim is:—

1. In a car coupler, the combination with 65 a car having one end hinged at the lower edge, and a coupler provided with a coupling pin having an eye, of an upright rod guided to slide on the car end and extending to the top, said rod having a bottom portion 70 extending out to engage the coupling pin, a snap hook on the end of said extension engaging the pin eye and adapted to be disengaged without dismounting the rod or the pin, a lever pivoted on the car end sill and 75 provided with a hook at its end engaging said rod extension, and adapted to be disconnected from said rod without dismounting of the lever or the rod, whereby the car end can be swung down on the bottom of 80 the car.

2. The combination with a car body having a coupler and coupling pin provided with an eye, of a rod slidably and rotatably mounted on the car body end, an extension 85 on said rod having means at its end normally engaging the eye of the coupler pin, said means being disengageable from said eye by rotation of the rod in one direction, a lever pivoted to the car end and having 90 means at its inner end normally engaging said extension, said extension being disengageable from the lever by rotation of the rod in the opposite direction to its rotation when disengaging from the coupler pin. 95

Signed at New York city, N. Y., on June 23rd 1920.

LUELLA CORNELL.
